(57) CLAIM

The ornamental design for a handbag, as shown and described.

DESCRIPTION

FIG. 1 is a front perspective view of a handbag showing my new design;

FIG. 2 is a front view thereof;

FIG. 3 is a back view thereof;

FIG. 4 is left side view thereof;

FIG. 5 is a right side view thereof;

FIG. 6 is a top view thereof; and,

FIG. 7 is a bottom view thereof.

The broken line crossing claimed surfaces on the bottom of the bag in FIG. 7 depicts a structural line and forms no part of the claim. The broken lines in FIG. 6 depict portions of the handbag that form no part of the claim.
